ELECTRIC DISCHARGE DEVICE

Vladimir K. Zworykin, Philadelphia, Pa., and Louis Malter, Newark, N. J., assignors to Radio Corporation of America, a corporation of Delaware

Original application January 31, 1936, Serial No. 61,680, now Patent No. 2,150,573, dated March 14, 1939. Divided and this application September 8, 1938, Serial No. 228,900

8 Claims. (Cl. 250—36)

Our invention relates to electronic oscillators and multipliers. More specifically, our invention is an electronic oscillator or amplifier in which the number of electrons is multiplied by secondary emission.

This application is a division of our Patent No. 2,150,573, which issued March 14, 1939 on a pending application, Serial No. 61,680, entitled "Electric discharge devices" and filed January 10, 1936.

We are aware of numerous ultra high frequency oscillators which operate as electronic oscillators. Oscillators of this type are broadly known as magnetrons, or Barkhausen-Kurz oscillators. We are also aware of electronic multiplication devices in which secondary emission increases the total number of electrons flowing in a given circuit. Among the objects of the present invention is to combine the operating 20 characteristics of a magnetron oscillator or amplifier and an electron multiplier.

Another object is to generate ultra high frequency oscillations in a vacuum tube employing cold electrodes which are secondarily emissive. 25 An additional object is to couple a driver circuit which is energized by the emission of secondary electrons to an oscillatory circuit whereby sustained oscillations are established. A still further object is to devise an electronic oscillator-multiplier device employing electrostatic fields only. Additional objects will appear in the accompanying specification and appended claims.

In the accompanying drawing,

Figure 1 is a schematic diagram of an electronic oscillator device,

Fig. 2 is a modified form of oscillator utilizing hollow electrodes, and

Fig. 3 is a further modification of the hollow electrode oscillator.

The theory of operation of our invention involves an understanding of electronic oscillators, secondary emission and electronic multipliers. The theory of the operation of these devices is complicated and not thoroughly understood. 45 However, since the theory may be an aid to an understanding of our invention we shall present a tentative theory of operation but do not intend to thereby limit our invention.

In an electronic oscillator of the split anode type, electrons are emitted by a heated cathode. Under the influence of a magnetic field whose lines of force surround the cathode and are substantially parallel thereto the electrons, emitted by the cathode, follow a curved path from the cathode toward the anodes. If the magnetic field

is of suitable strength, the transit time of electrons will be such that ultra high frequency oscillations will be established in a tuned circuit connected between the anodes. The frequency of such oscillations depends primarily upon the magnetic field strength. The oscillatory frequency may also depend on the resonant period of the circuit connected to the anodes.

The theory of secondary emission is as follows: If electrons moving at high velocity strike an electrode surface, secondary electrons are emitted. The number of such secondary electrons will depend upon the velocity of impact and the nature of the surface material of the electrode upon which the primary electrons impinge.

The theory of electronic multipliers is based primarily upon the theory of secondary emission. If primary electrons impinge at sufficient velocity on a suitable electrode, this electrode will emit a large number of secondary electrons. These electrons may be accelerated and impinged on a second electrode which in turn will emit still more secondary electrons. In this manner the number of electrons may be increased and multiplied many fold.

We propose to combine several of these effects whereby a single device may be used as an electronic oscillator-multiplier. One device embodying our invention is illustrated in Fig. 1.

In Fig. 1 the evacuated envelope 51 is preferably of annular or toroidal shape. Within the inner and outer circular walls of this envelope are suitably mounted at 90° intervals four grid-like electrodes 53. Each of these electrodes is made secondarily emissive. Oppositely disposed electrodes are connected together by leads 55 and 57. Between these leads is serially connected a tunable circuit 59 and an accelerating voltage source 61. The tunable circuit comprises an inductor 63 and a variable capacitor 65.

The magnetic field is applied so that its lines of force are substantially parallel to the surfaces of the grid-like electrodes. The electron path is substantially circular and is represented by the dash line 67.

The theory of operation of this circuit will now be given. Under the accelerating influence of the magnetic field and the positively charged electrodes, primary electrons will be emitted from the negative electrodes. These electrons will strike the positively charged grids and will emit secondary electrons. If the tunable circuit is resonant and if its ratio of reactance to resistance is sufficiently high, a transient voltage will

be established whereby an instantaneous positive voltage will be placed on the electrodes which were previously negative.

This instantaneous positive charge will attract 5 the secondary electrons with sufficient velocity to cause increased numbers of secondary electrons to be emitted when they strike the temporarily positive target. The phasal relation between the transient and the electronic motion 10 will be such as to result in the building up of sustained oscillations in the tuned circuit.

Fig. 2 is a schematic illustration of our invention in which electrostatic forces only are employed. In this figure, within a suitable envelope 15 91 four hollow electrodes, 93, are arranged to form a substantially rectangular path. Each of these electrodes resembles a hollow L or a hollow irregular T. The hollow section of each of these electrodes may be a circular section. It will be 20 observed that the several electrodes have three openings at the ends thereof. Oppositely disposed pairs of these electrodes are joined by connecting wires 95 and 97. Between these wires, 95, 97, are serially connected a tunable 25 circuit 99 and a battery 101. The tunable circuit comprises a variable capacitor 103 and an inductor 105. The ratio of the reactance to the resistance of this circuit should be high.

The theory of operation of this circuit is substantially the same as that of Fig. 1. It is assumed that electrons will be emitted from each of the instantaneous negative electrodes and will be accelerated at high velocity toward the instantaneous positive pairs of electrodes. The 30 surfaces of these electrodes, which act as targets, are made secondarily emissive and liberate increased numbers of secondary electrons. These secondary electrons are in turn accelerated at high velocities toward the next succeeding instantaneous positive electrodes. The electron paths are represented by the dash line 107.

It will be apparent that the instantaneous voltage of the tunable circuit 99 must exceed the voltage of the battery 101 if sustained oscillations are to be generated. If this circuit is resonant and has a low resistance in relation to its reactance, the currents flowing in the resonant circuit will be sufficient to establish the required potentials. In this as in the other figures, it is 40 preferable to have the resonant period of the oscillatory circuit suitably related to the time between successive electron movements or multiples thereof.

In Fig. 3 the envelope 91 and the electrodes 55 111, 113, 115, 117 are similar to those of Fig. 2. The circuit arrangements illustrated by this figure differ from those of Fig. 2. In the present circuit, each of the adjacent electrodes beginning with 111 are connected as follows: An oscillatory circuit 119 is connected to the first electrode 111 and to the negative terminal of a battery 121. The positive terminal of this battery is connected to the second electrode 113. The negative terminal of the battery 121 also is connected to a 65 second oscillatory circuit 123. This oscillatory circuit 123 in turn is connected to the third electrode 115 and to a third oscillatory circuit 125. This oscillatory circuit is connected to the negative terminal of a second battery 127. The positive terminal of battery 127 connects to the fourth electrode 117. The negative terminal of battery 127 is also connected to a fourth oscillatory circuit 129. This oscillatory circuit is connected to the first mentioned electrode 111.

70 Of these oscillatory circuits, the first and third

mentioned 119, 125 are the circuits which deliver energy to the electrons resulting in secondary emission, the second and fourth mentioned circuits 123, 129 are the circuits which abstract energy from the electrons so as to maintain 5 oscillations within these circuits. The circuit 119 and the circuit 129 are suitably coupled by mutual magnetic coupling M or the like. The circuit 123 and the circuit 125 are likewise coupled. No magnetic field is required in this 10 circuit arrangement. The electrostatic field provides the necessary force. In this arrangement, electrons emitted from the instantaneously negative electrodes approach the next adjacent instantaneously positive electrode but do not strike 15 this target as the instantaneous polarity changes during the electron movement so that the next succeeding target is struck by the electrons at high velocities. The impact of these electrons liberates secondary electrons which are in turn 20 carried around the electron path 131. The mutual coupling between the pairs of oscillatory circuits provides the necessary feedback path by means of which sustained continuous oscillations are generated. 25

It should be understood that various combinations of parts which are represented in the several illustrations of our invention may be combined, also a thermionic oscillator may be employed in connection with any of the embodiments illustrated in the figures in order to provide a driving voltage. Likewise, an amplifier coupling may be employed to couple the oscillatory circuits of any of the several figures. 30

Although we have illustrated electronic devices in which four secondarily emissive electrodes are employed it should be understood that our invention is not limited to this specific arrangement. Any even number of secondarily emissive electrodes may be employed. Likewise, 40 we have described electrodes of cylindrical shape. This particular shape is not essential and plane electrodes may be substituted.

Other modifications within the scope of our invention will occur to those skilled in the art. 45 The foregoing examples are by way of illustration of our invention and are not to be taken as limitations of form or circuit.

We claim:

1. In an electronic oscillator-multiplier at 50 least four electrodes having electron emissive surfaces, said emissive surfaces being the principal source of electron emission for said oscillator-multiplier, means electrically connecting alternately disposed electrodes, an oscillatory circuit and a source of polarizing potential serially connected between two adjacent emissive electrodes, so that electrons impinge on each electrode and release secondary electrons which pass to an adjoining electrode in a predetermined 55 sequence.

2. In an electronic oscillator-multiplier at 60 least four electrodes having electron emissive surfaces, said emissive surfaces being the principal source of electron emission for said oscillator-multiplier, means electrically connecting alternately disposed electrodes, and means for impressing a fixed biasing potential and a superimposed alternating potential between adjacent emissive electrodes, so that electrons impinge on 65 each electrode and release secondary electrons which pass to an adjoining electrode in a predetermined sequence.

3. In an electronic oscillator-multiplier at 70 least four electrodes having electron emissive 75

- surfaces, said emissive surfaces being the principal source of electron emission for said multiplier-oscillator, means electrically connecting alternately disposed electrodes, means for impressing a fixed biasing potential and a superimposed alternating potential between adjacent emissive electrodes, and means for creating a magnetic field whose lines of force intersect said electrodes.
- 10 4. A device of the character described in claim 1 in which said emissive electrodes are hollow members having their inner surfaces electron emissive.
- 5 5. A device of the character described in claim 1 in which said emissive electrodes are grid-like structures arranged mutually at right angles to each other.
- 10 6. In an electrical discharge device an evacuated envelope, a plurality of hollow electrodes supported in symmetrical relation within said envelope and including electron emissive inner surfaces, an oscillatory circuit, a source of biasing potential, and means connecting said oscillatory circuit and said course of biasing potential between pairs of said electrodes, said electrodes having adjacent openings so that a continuous electron path is formed through each of said hollow electrodes in succession.
- 20 7. In an electronic oscillator-multiplier, an annular shaped evacuated envelope, a plurality of grid electrodes disposed in said envelope at substantially uniform intervals, means for rendering the surfaces of said electrodes electron emissive, an oscillatory circuit, a source of biasing voltage, means serially connecting said circuit and said source between oppositely disposed pairs of said electrodes, and a magnetic field whose lines of force are substantially parallel to the surfaces of said electrodes whereby electrons emitted from said surfaces travel in curved paths between said electrodes and sustain oscillations in said circuit.
- 20 8. In an electrical discharge device an evacuated envelope, a plurality of hollow electrodes supported in symmetrical relation within said envelope and including electron emissive surfaces, a plurality of serially connected oscillatory circuits, means respectively connecting said hollow electrodes to the common terminals of said oscillatory circuits, whereby a continuous electron path is established through said hollow electrodes, and continuous oscillations are generated.
